Primary Examiner — T Chase Nelson*Assistant Examiner* — Jonathan J. Han(74) *Attorney, Agent, or Firm* — Sterne, Kessler, Goldstein & Fox PLLC.(57) **CLAIM**

The ornamental design for a shoe, as shown and described.

DESCRIPTION

FIG. 1 is a top front perspective view of a shoe showing the claimed design;

FIG. 2 is a front view thereof;

FIG. 3 is a left side view thereof;

FIG. 4 is a right side view thereof;

FIG. 5 is a top view thereof;

FIG. 6 is a top front perspective view of the shoe of FIG. 1 shown in an expanded configuration; and,

FIG. 7 is a left side view thereof shown in an expanded configuration.

The broken lines in the figures show portions of the shoe that form no part of the claimed design. The broken lines on the claimed portion of the shoe surrounded by shading depict stitching, which forms no part of the claimed design.

1 Claim, 7 Drawing Sheets(56)
